(57) **CLAIM**

The ornamental design for a toilet bowl, as shown and described.

DESCRIPTION

FIG. 1 is a right side elevation view of the toilet bowl that comprises my invention;

FIG. 2 is a front view thereof;

FIG. 3 is a top view thereof;

FIG. 4 is a left side perspective view thereof;

FIG. 5 is a right side elevation view thereof with open lid;

FIG. 6 is a front view thereof;

FIG. 7 is a top view thereof;

FIG. 8 is a left side perspective view thereof;

FIG. 9 is a right side elevation view of a second embodiment of the toilet bowl that comprises my invention;

FIG. 10 is a front view thereof;

FIG. 11 is a top view thereof;

FIG. 12 is a left side perspective view thereof;

FIG. 13 is a right side elevation view thereof with open lid;

FIG. 14 is a front view thereof;

FIG. 15 is a top view thereof; and,

FIG. 16 is a left side perspective view thereof.

Delete Figs. 9-16.

Signed and Sealed this
Tenth Day of July, 2012

David J. Kappos
Director of the United States Patent and Trademark Office

UNITED STATES PATENT AND TRADEMARK OFFICE
CERTIFICATE OF CORRECTION

PATENT NO. : D658,277 S
APPLICATION NO. : 29/396585
DATED : April 24, 2012
INVENTOR(S) : Daniel Iranyi, Tom Stäubli and Arno Lenzi

Page 1 of 8

It is certified that error appears in the above-identified patent and that said Letters Patent is hereby corrected as shown below:

Delete the title page and substitute therefore the attached title page consisting of corrected description and number of drawing sheets in patent.

Delete Drawing Sheets 1-12 and substitute therefore the attached Drawing Sheets 1-6. Figs. 9-16 have been cancelled.

This certificate supersedes the Certificate of Correction issued July 10, 2012.

Signed and Sealed this
Fourteenth Day of August, 2012

David J. Kappos
Director of the United States Patent and Trademark Office
